DESIGN FOR A SPRAY HEAD OR THE LIKE

Henry Dreyfuss, New York, N. Y., assignor to Crane Co., Chicago, Ill., a corporation of Illinois

Application July 30, 1945, Serial No. 121,085

Term of patent 14 years

(Cl. D91—3)

To all whom it may concern:

Be it known that I, Henry Dreyfuss, a citizen of the United States, residing at New York, in the county of New York and State of New York, have invented a new, original, and ornamental Design for a Spray Head or the Like, of which the following is a specification, reference being had to the accompanying drawing, forming part thereof.

Fig. 1 is a plan view of the spray head embodying my new design;

Fig. 2 is a side view thereof;
Fig. 3 is a bottom view thereof, and
Fig. 4 is an end view.

I claim:

The ornamental design for a spray head or the like, substantially as shown.

HENRY DREYFUSS.
